UNITED STATES PATENT OFFICE.

CHARLES C. SPREEN, OF DETROIT, MICHIGAN, ASSIGNOR TO ELECTRIC REFRIGERATION CORPORATION, OF DETROIT, MICHIGAN, A CORPORATION OF MICHIGAN.

MECHANICAL REFRIGERATION.

Application filed July 27, 1926. Serial No. 125,188.

My invention relates to mechanical refrigeration, and particularly to sectional expansion units for mechanical refrigerating apparatus of the compressor-condenser-flooded-expander type and the particular object of my invention is to provide new and improved sectional expansion units particularly applicable to this use. In the drawings accompanying this specification and forming a part of this application I have shown, for purposes of illustration, one form which my invention may assume. In these drawings:

Figure 1 is a side elevation of this illustrative form of my invention,

Figure 2 is an end elevation of this illustrative embodiment of my invention, while

Figure 3 is a section on the line 3—3 of Figure 2.

The embodiment of my invention herein shown and described comprises a pair of end sections 12 and 121, the section 12 comprises an upper connecting portion 13 arranged to receive at either end either a nipple 14 connecting that upper connecting portion 13 with the upper connecting portion of an adjacent section, or a plug 15 closing that end of that upper connecting portion 13, the section 121 comprises a similar upper connecting portion 131 arranged to receive at one end either a nipple 14 connecting that upper connecting portion 131 with the upper connecting portion of an adjacent section, or a plug 15 closing that end of the upper connecting portion 131, each of the sections 12 and 121 comprises a lower connecting portion 16 arranged to receive at either end either a nipple 17 connecting that lower connecting portion 16 with the lower connecting portion 16 of an adjacent section, or a plug 18 closing that end of that lower connecting portion 16, the section 12 comprises a central heat transferring portion 19 extending between and in communication with the upper and lower connecting portions 13 and 16 of that section, the section 121 comprises a central heat transferring portion 191 extending between and in communication with the upper and lower connecting portions 131 and 16 of that section, and each of the portions 19 and 191 is provided on either face with a plurality of fins 20 serving to increase the transfer of heat into or from the heat transferring portion 19 or 191 and, in cooperation with

the fins 20 of an adjacent section, to provide suitable supports for receptacles 21 for the formation of artificial ice.

Integral with the upper connecting portion 131 and heat transferring portion 191 of the section 121, and in communication therewith, is a chamber 221 arranged to receive the control valve means for regulating the flow of liquid refrigerant into the expansion unit, this chamber 221 comprising a vertical cylindrical body 231 integral with the upper connecting portion 131 and heat transferring portion 191 of the section 121, provided near its top with a refrigerant outlet 261, closed at the bottom by an integral base wall 241 provided with a refrigerant inlet 271, and closed at the top by a removable top wall 251, the top wall 251 and bottom wall 241 serving together to support for vertical reciprocation a float 301 carrying a valve 291 arranged to close the refrigerant inlet 271 when the float is raised by the presence within the chamber 221 of refrigerant to the desired level.

From the above description it will be apparent to those skilled in the art that I have provided a new and improved sectional expansion unit particularly adapted for use with refrigerating apparatus of the compressor-condenser-flooded-expander type. At the same time, it will also be obvious to those skilled in the art that the particular embodiment of my invention herein shown and described may be variously changed and modified without departing from the spirit of my invention or sacrificing the advantages thereof, and it will accordingly be understood that the disclosure herein is illustrative only and that my invention is not limited thereto.

I claim:

1. In a mechanical refrigerating apparatus of the compressor-condenser-flooded-expander type, an expansion unit comprising a pair of end refrigerating sections connected with their interiors in operative communication, a chamber for the reception of control valve means at the side of and integral with one of said end refrigerating sections with its interior in operative communication with the interior of said end refrigerating section, and control valve means operatively positioned within said chamber.
2. In a mechanical refrigerating appara-

tus of the compressor-condenser-flooded-expander type, a sectional expansion unit comprising a refrigerating section arranged to be connected with its interior in operative communication with the interiors of other sections and comprising a chamber for the reception of control valve means at the side of and integral with said refrigerating section with its interior in operative communication with the interior of said refrigerating section. In testimony whereof I hereunto affix my signature.

CHARLES C. SPREEN.
